LAVATORY CABINET

Harry G. Coordes, Detroit, Mich., assignor to
Briggs Manufacturing Company, Detroit, Mich.,
a corporation of Michigan

Application October 5, 1936, Serial No. 104,008

6 Claims. (Cl. 312—169)

This invention relates to lavatories, sinks, washbasins and similar articles, and more particularly to articles of the above character used in combination with cabinet structures.

5 An object of the invention is to provide a knock-down lavatory cabinet structure including a pressed metal base, a pressed metal cabinet detachably mounted on the base, and a sink or washbasin, preferably pressed from sheet metal, detachably mounted on the cabinet.

A further object of the present invention is to provide a combined lavatory cabinet structure which is composed of a plurality of unitary structures adapted to be connected together with the aid of simple means, such as a few bolts or screws, such construction permitting separate manufacture of said unitary structures without the necessity of handling the entire lavatory cabinet before the time of final installation.

20 Another object of the invention is to provide a knock-down lavatory cabinet structure which can be packed and shipped to the place of installation in unassembled condition, thus permitting careful and separate packing of such parts as enameled side panels and doors, and yet permitting the same to be easily assembled in place by an unskilled workman.

A further object of the invention is to provide a knock-down lavatory and cabinet structure comprising as separable parts a basin, a cabinet, and a base adapted to be readily joined together to form a complete structure, the improved arrangement being such as to permit the basin, cabinet and base parts to be manufactured in a variety of colors and the assembled units to be furnished to customers in many different color combinations.

Other objects of this invention will appear in the following description and appended claims, reference being had to the accompanying drawings forming a part of this specification wherein like reference characters designate corresponding parts in the several views.

Fig. 1 is an exploded perspective rear view of the combined lavatory cabinet constructed in accordance with the present invention, showing the lavatory cabinet ready for assembly at a place of installation.

Fig. 2 is a perspective view of the detachable base.

Fig. 3 is a perspective front view of the lavatory cabinet structure of Fig. 1 as the same appears in assembled condition.

55 Fig. 4 is a top view, partly in section, of the structure shown in Fig. 3 with the lavatory removed, the view being taken on the line 4—4 of Fig. 3.

Fig. 5 is a perspective sectional view of the upper left rear corner of the assembled lavatory

cabinet looking in the direction of the arrows, section being taken on the line 5—5 of Fig. 3.

Fig. 6 is a fragmentary front view, partly in section, taken on the line 6—6 of Fig. 4 and showing the front of the left corner of the cabinet and base.

Fig. 7 is a sectional view looking in the direction of the arrows, section being taken on the line 7—7 of Fig. 6, said figure illustrating the method of door suspension.

Fig. 8 is another sectional view illustrating the method of supporting the floor of the cabinet at the base, section being taken on the line 8—8 of Fig. 6.

Fig. 9 is a fragmentary perspective view of the left hand upper rear corner of the cabinet.

Fig. 10 is a fragmentary perspective view of a corner of the cabinet structure subjacent to the upper corner shown in Fig. 9, said view also showing the rear left hand shelf support.

Fig. 11 is another fragmentary perspective view showing the left hand lower rear corner of the cabinet and base.

Fig. 12 is a fragmentary perspective view of the left hand front corner of the cabinet showing the method of door suspension as well as the method of connecting the inner and the outer sheets of the side panel of the cabinet.

Fig. 13 is a view similar in part to Fig. 12, the outer sheet of the side panel being removed to show the flanges of the inner sheet at said corner.

Fig. 14 is a fragmentary perspective view of the front left hand shelf support provided in the cabinet subjacent to the corner shown in Figs. 12 and 13.

Fig. 15 is another fragmentary perspective view illustrating the method of connecting the floor and the sides of the cabinet, as well as the method of connecting the cabinet and the base at the lower left front corner of the lavatory cabinet.

Fig. 16 is a fragmentary sectional view taken on the line 16—16 of Fig. 3.

Fig. 17 is a fragmentary sectional view taken on the line 17—17 of Fig. 6.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring to the drawings, there is illustrated therein, by way of example, a lavatory cabinet embodying the present invention. As shown in Figs. 1 and 3 the lavatory cabinet structure con-

sists of a sink **S**; a cabinet frame **C**; two symmetrical side panels **P**, **P**; two symmetrical doors **D**, **D**; and a base **B**. The lavatory cabinet may leave the manufacturing plant with all of said elements being separate. I have found that in many instances the frame **C** and base **B** may be connected together at the plant and handled as a single unit thereafter.

In assembling the structure, the first operation is to connect the cabinet frame **C** with the base **B**, unless said cabinet and said base are shipped to the place of installation as a single unit, as mentioned. Thereupon, the side panels **P**, **P** are put in place and connected to the cabinet frame **C** with a plurality of screws or bolts. The sink **S** is next placed on the top of cabinet frame **C**, their corner plates and holes therein being alined. Bolts are inserted through said holes and nuts are tightened on said bolts. When so assembled, the structure forms a combined lavatory cabinet structure accomplishing the objects hereinbefore mentioned and possessing many other advantageous features.

The sink or washbasin **S** is formed by stamping operations from a single sheet metal blank. It is adapted to be provided in the assembled condition with a number of suitable water faucets, and its overflow and drain holes are adapted to be connected with a suitable drain pipe beneath the basin. The cabinet frame **C**, the side panels **P**, **P**, as well as the base **B** are made up in the present embodiment from a number of sections stamped out from sheet metal, said sections being connected together by spot welding and screws. The cabinet is provided with a bottom or floor, a number of suitable shelves, and a double or a single door. Parts, the thickness of which is apparent to the observer, such as doors and side walls, are made thick and hollow in order to impart to the structure a massive appearance of pleasing contour. All exterior exposed surfaces of the lavatory, side panels, and base are specially treated to provide an attractive, durable enamel finish. Any desired color combination may be produced in the lavatory cabinet of my invention by a proper selection of colors for the basin, side panels, doors and base.

Referring more particularly to Figs. 1 and 3, the basin or sink **S** comprises a substantially horizontal table portion **20** having a suitable basin or fluid receiving bowl **21** formed substantially at its middle. The basin **21** is provided with a suitable drain hole **21a** and an overflow hole **21b**. Suitable hot and cold water faucets **24**, **24** admitting hot and cold water in desired proportion to a mixing spout **23** are provided at the horizontal table portion **20** in assembling the structure. The horizontal table portion **20** is surrounded at its four sides with a continuous rolled rim **25**, which rim merges at its outside edges into a continuous depending apron **26**. The apron **26** extends downwardly around all four sides of the table **20**, and its lower edges are provided with an inwardly extending substantially horizontal flange **27**. The flange **27** is adapted to rest upon the upper flanges of the side panels **P**, **P**. At all four corners formed by the apron **26** there are provided corner plates **28**, **28** (see Fig. 1) secured to the flange **27** in any suitable manner, preferably by spot welding. Each of said plates **28**, **28** is provided with a hole **29**.

The cabinet frame **C** comprises two symmetrical side sheets **30** and **31**, back bracing consisting of a narrow angular tie **32** and a wide lower tie **33**; a floor sheet **34** connecting the side sheets at

the lower edges thereof; and an upper front channel **35** connecting the side sheets **30** and **31** at their front upper corners. The channel **35** is bent or bowed outwardly as shown in Fig. 4. The above specified members being fixed together in the manner described below in detail, the cabinet frame **C** forms a rigid and strong frame, constituting the structural foundation of the lavatory cabinet to which foundation other structural units, namely the doors **D**, **D**, the sink **S**, the side panels **P**, **P**, and the detachable base **B** are attached.

The side sheets **30** and **31** are symmetrical in construction. Along their top edges said sheets are provided with inwardly extending substantially horizontal flanges, such as flange **36** of the sheet **30**, while along their vertical back edges said sheets are provided with inwardly extending flanges **38** and **39**, respectively. Along their front vertical edges the side sheets **30** and **31** are provided with inwardly extending wide flanges **40** and **41**, which flanges are, in turn, provided with narrow forwardly extending flanges **42** and **43** (Fig. 14). Along the top edges of said wide flanges **40** and **41** there are provided narrow substantially horizontal flanges such as flange **44** of sheet **30** (see Fig. 13). In the present embodiment of the invention, there are no horizontal flanges provided along the lower edges of the sheets **30** and **31**. At the top portions of the wide front flanges **40** and **41** the sheets **30** and **31** are connected together by means of the front channel **35** secured to said flanges by the extremities of its web. Plate **46** is secured, preferably by spot welding, to the upper flanges **47** and **36** of the channel **35** and the side sheet **30**, respectively, as shown in Fig. 13. Similar plates are provided at each of the four upper corners of the cabinet frame **C**. Holes **48**, **48** are provided in the corner plates **46**, **46** and the same are in alinement with the respective holes **29**, **29** of the corresponding plates **28**, **28** of the washbasin.

The back braces or ties **32** and **33** are secured by the extremities of their vertical flanges to the vertical back flanges **38** and **39** of the side sheets **30** and **31**, as is shown in Figs. 1, 9 and 11.

The floor sheet **34** is provided at its edges with a depending narrow apron **49**, the front portion whereof is provided with a substantially horizontal inwardly extending flange **50** (see Fig. 15). The apron **49** of said floor sheet **34** is secured, preferably by spot welding, to the lower edges of the sheets **30** and **31** (see Fig. 15). Within the cabinet frame there are provided a number of suitably arranged shelves **51**, **51** supported by brackets **52** spot welded to the cabinet frame structure or connected thereto in any suitable manner.

The detachable base **B** shown separately in Fig. 2 is designed to provide support for the entire structure, and is made concaved in front to provide the necessary toe room. In the present embodiment, the base **B** comprises side members **53** and **54** suitably shaped in front to provide said toe room, a front member **55** and a rear member **56**. Said members **53**, **54**, **55** and **56** are flanged as shown and are connected in any suitable manner to form a substantially rectangular structure. Members **53** and **54** are provided with supporting angular flanges **57** and **58** which flanges in the assembled condition bear upon the bottom surface of the floor sheet **34**.

For securing the base **B** to the cabinet frame **C**, the cabinet frame is superimposed upon the base, flanges **57** and **58** coming in contact with **75**

the floor sheet 34 of the cabinet frame, whereupon the base is attached to the frame with a plurality of bolts 59. A supporting channel member 60 is provided between the front member 55 and the floor sheet 34.

5 A double door structure D, D is exemplified in the present embodiment, each door, consisting of inner and outer panels. Each door comprises a shallow pressed-out box-like front panel 61 having rearwardly extending flange 62, the corners of the panel being rounded as at 63, Fig. 4. The back flanged panel 64 is fitted into the front panel (see Fig. 4) and is securely affixed thereto. I prefer to use a double door, the respective halves being suitably hinged as at the upper hinge piece 65 secured to the front channel member 35 and the lower hinge 66 secured to the flange 50 of the floor sheet. In proximity to their meeting edges, door panels D, D are provided with suitable 15 handles 67, 67. However, it is to be understood that I do not desire to be limited to the double door construction, since a single door may be advantageous in some particular instances. With the double door construction adopted in the present embodiments, the panels D, D carry at their upper outside corners angle brackets 68, 68 (see Fig. 12) provided with suitable pivots entering respective holes in the hinge pieces 65, 65. At their lower outside corners the panels D, D are 20 provided (see Fig. 7) with suitable holes adapted to receive pivots 69, 69 carried by the lower hinge pieces 66, 66. Suitable, preferably brass, washers 70, 70 are provided at pivots 69, 69 and they may be slightly lubricated to ensure easy and noiseless 25 operation of the door.

One, or both, of half-doors D, D is provided with a suitable self-operating latch, Fig. 16. In the present embodiment the same is exemplified by a spring operated latch consisting of a bracket 40 71 affixed to the door panel 64 and carrying a tapered plunger 72 cooperating with a catch 13 affixed to the channel 35. The plunger 72 is adapted to be maintained in its extended position by a suitable spring housed within the bracket 45 71. In the position of the plunger shown in Fig. 16, a certain effort is necessary to open the door, which prevents selfopening of the door. It may be desirable in some instances to have the latch of the foregoing character provided at one of the half-doors, selfopening of the second half-door being prevented by a suitable lock or latch provided within the respective handle 67.

Each of the side panels P, P comprises a side portion 74 provided with an upper flange 75, a back flange 76, and a lower flange 77, as shown in Fig. 1. Along its vertical front edge, the side portion 74 merges smoothly and seamlessly into the front flange portion 18 provided along its edges with a vertical inwardly extending flange 79. For securing the left panel to the cabinet frame C, said panel is arranged at the respective side of the frame in such a manner that the lower flange 77 enters the slot between the lower edge of the sheet 30 and the respective shoulder 80 of the side member 53 of the base B (see Fig. 11), causing the back flange 76 to bear against the back flange 38 of the inner sheet 30 (see Figs. 11, 10 and 9) and the upper flange 75 to rest at the upper flange 36 of the sheet 30. A suitable 50 gasket is placed between the flanges 76 and 38, and said flanges are securely connected together with the aid of screws 81, 81. The method of attaching the right panel to the cabinet frame is

similar to the above described method of attaching the left panel. Suitable stops or bumpers 82, 82 are provided at front portions 18, 18 of the panels P, P to prevent their scratching by the door panels D, D when the same are fully opened. Similar bumpers 83, 83 are secured at the channel member 35 (see Fig. 16) and the same serve as stops for the doors D, D in closed position thereof. 5

I claim:

1. In a combined lavatory cabinet having a 10 cabinet frame, a sink pressed out from a single sheet metal blank to provide a horizontal table portion, a basin in said portion, a continuous depending apron around all four sides of said portion, and an inwardly extending flange around 15 the lower edges at said apron; and means provided at said flange adapting the sink to be secured to the subjacent cabinet frame, said means comprising superimposed corner plates carried by the flange and the adjacent portion of the cabinet 20 frame.

2. A knock-down lavatory cabinet comprising a sink having a basin portion, a cabinet frame having an open top, a supporting base, two side panels, means for detachably connecting said 25 cabinet frame to said base, means for detachably securing said side panels to said cabinet frame, and means for detachably mounting said sink on said cabinet frame with the basin portion thereof projecting into the open top of said 30 frame, said last means comprising corner plates carried by the sink and frame and bolts for securing the plates together.

3. A combined lavatory cabinet comprising a rigid pressed metal cabinet frame having an open 35 top and a floor, a pressed metal supporting base, a sink having a portion extending into said open top, said base and sink being detachably secured to said cabinet frame, said sink and frame having cooperating corner plates and said base having 40 a pair of upstanding flanges adapted to bear against said cabinet floor, and means for connecting the corner plates together.

4. In a combined lavatory cabinet including a sink and a cabinet having a floor, said sink 45 being mounted upon and providing a top for the cabinet, a detachably pressed metal base having inturned top and bottom flanges on four sides thereof, means for securing said base to said cabinet structure subjacent thereto, and supporting flanges located above the top flange at 50 two sides of the base adapted to bear against the floor of the cabinet.

5. In a combined lavatory cabinet having a cabinet frame, a sink pressed out from a single 55 sheet metal blank to provide a horizontal table portion, a basin in said portion, a continuous depending apron around all four sides of said portion, and an inwardly extending flange around the lower edges at said apron; corner plates provided at said flange, corner plates at the top corners of the cabinet frame cooperating with said first named plates, and means interconnecting the plates for securing the sink to said cabinet frame.

6. In a combined lavatory cabinet including a sink and a cabinet having a floor, a detachable pressed metal base having top and bottom flanges, said top flanges providing means for securing said base to said cabinet structure subjacent thereto, and a supporting flange adapted 70 to bear against said floor of the cabinet.

HARRY G. COORDES.

CERTIFICATE OF CORRECTION.

Patent No. 2,146,939.

February 14, 1939.

HARRY G. COORDES.

It is hereby certified that error appears in the printed specification of the above numbered patent requiring correction as follows: Page 3, second column, line 47, for the word "detachably" read detachable; and that the said Letters Patent should be read with this correction therein that the same may conform to the record of the case in the Patent Office.

Signed and sealed this 11th day of April, A. D. 1939.
